UNITED STATES PATENT OFFICE.

BEN H. PARKER AND CLARENCE DONALD BEETH, JR., OF LAMAR, COLORADO.

ELECTROMAGNETIC HAMMER.

Application filed August 22, 1927. Serial No. 214,640.

This invention relates to electro-magnetic hammers and is adapted particularly for use in connection with hammer type rock drills, riveting machines, chiseling machines, and other machines using a hammer blow during the operation thereof. An important object of the invention is to provide a reciprocally mounted hammer arranged for actuation by a series of electro-magnets and embodying a pneumatic cushioning construction adapted to arrest the return stroke of the hammer.

Another object is to provide an apparatus of this character of simple and practical construction, efficient and reliable in performance, strong and durable, and otherwise well adapted for the purposes for which the same is intended.

Other objects and advantages reside in the special construction and combination of the various elements forming a part of the invention, reference being had to the accompanying drawings forming a part hereof, wherein:

Figure 1 is a view in elevation with parts shown in vertical section illustrating the relative position of the electro-magnetic members.

Figure 2 is a similar view showing the device in side elevation.

Figure 3 is a transverse sectional view taken substantially along a line 3-3 of Figure 1.

Figure 4 is a similar view taken along a line 4-4 of Figure 1.

Figure 5 is a similar view taken along a line 5-5 of Figure 1.

Figure 6 is a similar view taken along a line 6-6 of Figure 1.

Figure 7 is a group perspective of the electric contact sleeves and the insulation sleeve interposed therebetween.

Figure 8 is a detail illustrating the manner of connecting the sleeves with the armature core, and,

Figures 9 and 10 are diagrammatic views illustrating opposite magnetic effects produced by reversing the direction of the current in order to obtain the reciprocating movement of the hammer.

Referring to the accompanying drawings, we have disclosed our invention comprising a substantially cylindrical housing 5, preferably constructed of suitable light weight metal such as aluminum, and having its lower end closed by a base plate 6 and its

upper end closed by a head plate 7. Ears 8 are arranged on the head plate 7 to extend outwardly from the sides of the housing and having openings adapted to receive studs 9 extending through the plates with a nut 10 threaded on the lower ends thereof and having coil springs 11 disposed above and beneath the plates whereby to yieldably permit sliding movement of the studs therein. The upper end of the studs are connected by a cross member 12 having a handle 13 mounted thereon.

The base plate 6 is provided with a central opening about which is formed a bushing guide 14 having a tool chuck bushing 15 fitted therein and adapted to carry a tool chuck 16 therein. The tool chuck is adapted to receive a tool shank 17 having a drilling or other tool such as a bit 18 or the like formed at its lower end. The tool shank 17 is retained in position within the chuck by means of a tool retainer clip 19 having one end adapted to embrace the tool and having its opposite end secured to a retainer clip mounting 20 disposed beneath the base plate 6, said clip mounting and base plate having aligned openings formed therein for receiving rods 21 extending from the head plate 7 and secured in position with respect thereto by threaded nuts 22. Coil springs 23 are mounted on the lower ends of the rods whereby to tensionally secure the retainer clip mounting in position.

A striking hammer 24 is centrally arranged within the housing 5 and disposed immediately above the upper end of the tool shank 17 and adapted to be moved into and out of striking engagement therewith. The hammer 24 is carried by a movable electro-magnet formed of an armature core 25, which is of magnetic material and having a central bore for receiving an armature shaft 26 in slidable engagement therewith. The upper end of the armature shaft extends through the headplate 7 and is fixedly secured with respect thereto by a nut 27 and which is threaded on the upper end of said shaft.

Fixedly secured to the upper end of the armature core 25 is disposed a pair of cylindrical concentrically mounted sleeves 28 and 29, the upper ends of the sleeves being open permitting the same to be arranged in nested relation, the numeral 28 indicating the inner sleeve, and the numeral 29 indi-

cating the outer sleeve. An insulation sleeve 30 is interposed between the sleeves 28 and 29. Each of the sleeves is provided with a central opening in the lower end thereof through which the armature shaft 26 is inserted and bolts 32 secure the lower ends of the sleeve to the upper ends of the armature core 25. The sleeves 28 and 29 are formed of conductive material and have an insulation plate 33 interposed therebetween and the armature core to prevent electrical communication therebetween.

Upon the armature shaft 26 is mounted an insulated brush holder 34 supporting a contact brush 35 yieldably retained in contacting relation with the base of the inner sleeve 28 and a similar brush holder 36 is secured adjacent the outer face of the outer sleeve 29 having a contact brush 37 likewise yieldably contacting therewith. Electric wires 38 extend from the brushes outwardly through the head plate 7 to a suitable source of current.

One or more field magnet cores 39 are arranged to extend vertically through the housing 5 being threadedly secured at their opposite ends to the core and upper plates 6 and 7, said poles being formed in section of material of varying magnetic quality, the ends of the poles preferably being constructed of brass with the intermediate section preferably formed of soft iron in order to enhance the magnetic quality thereof, the ends of the sections forming the poles being joined as by welding at points indicated at 40.

The intermediate section of the poles constitutes a field magnet core shown at 41 about which is arranged an upper field magnet winding 42 and a lower field magnet winding 43. At each end of the windings 42 and 43 and arranged in magnetic connection with the field magnet core 41 are transversely arranged field magnet poles 44, said field magnet poles extending throughout the area within the housing 5 except for the openings necessary for the vertical sliding movement of the sleeves and the armature core. In the present form of this invention while we have indicated the use of a pair of such field magnet units, each consisting of a field magnet core 41, windings 42 and 43, and necessary lead-in wires 45, it is to be understood that the number of such units employed for use with the invention may be increased or decreased as desired. Field coil lead-in wires 45 connect the same with a suitable source of current.

The armature core 25 is provided with a suitable armature winding 46, a suitable electrical connection 47 being arranged to connect said winding with the contact sleeves 28 and 29. To energize the armature, current is fed from the source of supply through

one of the armature winding lead-in wires, then to one of the brushes 35 or 37, contacting with the sleeves 28 and 29, then by way of the electrical connection 47 to the armature winding and out through the other 70 armature winding connection and back to the source of supply.

The field magnet windings may be connected in series, in parallel, or in a combination of series and parallel in order to set 75 up the magnetic field as illustrated in Figures 9 and 10 of the drawings when current is supplied to the field coil lead-in wires.

The reciprocating movement of the armature carrying the striking hammer 24 is obtained by reversing the direction of current flow in either the field coils or the armature coil, but not both, and may be accomplished

in any suitable manner, a practical method of obtaining this result being shown by the 85 rotating commutators illustrated in Figs. 9 and 10, consisting of a pair of conductive rings 48, insulated from each other and mounted upon and insulated from a rotating shaft 49 together with four fixed brushes 90 arranged and connected as shown. This current reversing mechanism is a separate unit from the electro-magnet hammer proper and may be installed adjacent to or at a remote distance from the hammer itself. The 95 rotation of the shaft 49 upon which the armatures are mounted is obtained by any desired motive power, preferably an electric motor. The number of hammer blows imparted to the striking hammer 24 carried by 100 the armature, in an allotted time, is a function of the number of revolutions, in such allotted time, of the current reversing mechanism. If desired, the two conductive rings of such current reversing mechanism may 105 be so shaped and proportioned that the period of current flow which causes the hammer blow will be of a longer duration than the period of current flow which causes the return stroke of the striking hammer. This 110 action, in effect, would cause a magnetic cushioning for the striking hammer on its return stroke.

However, a more positive cushioning arrangement is provided for the striking hammer consisting of a pocket of air entrapped within the space between the lower ends of the armature shaft 26 and the striking hammer 24, as indicated at 51 and having a plurality of air ducts 52 communicating therewith. The armature shaft acting as a piston causes this pocket of air to be compressed, such compressing action resulting in the arresting of the movement of the striking hammer on its upward stroke to 115 prevent the same from contacting with the armature shaft. A suitable number of the air ducts 52 may be provided and arranged in such a position as to allow the partial return of the striking hammer without any ar- 120

resting action until the armature core has returned to such a position that an arresting of the return movement is necessary to prevent the complete return of the striking hammer with respect to the armature shaft. The exact position of the air ducts is a function of the speed at which the hammer is to be operated.

As soon as the return stroke of the striking hammer and armature core is completely arrested and the magnetism is reversed to cause the movement of the striking hammer in a downward direction which constitutes the hammer stroke, the compressed air within the cushioning device aids in the starting of the hammer stroke by tending to expand to its normal volume, and as soon as such volume has been reached the air ducts then occupy an open position with respect to the air pockets 51 so that air is free to enter the same and allow the completion of the hammer stroke without resistance of any low pressure within the pocket.

It is obvious that the invention is susceptible of various changes in the shape, size and arrangement of the various elements, without departing from the spirit or scope of the appended claims, and we accordingly claim all such forms of the device to which we are entitled.

We claim:—

1. In a device of the class described, a housing, a striking hammer arranged therein, a tool extending within the housing in striking engagement with said hammer, electro-magnetic means arranged within the housing operatively connected with said hammer whereby to reciprocally actuate the same, said hammer having an air pocket formed therein with air ducts communicating therewith and adapted to be closed by the upward movement of the hammer whereby to cause an air pressure within the pocket and arranged to react upon the hammer whereby to cushion the upward movement thereof.

2. In a device of the class described, a housing, a striking hammer arranged therein, a tool extending within the housing in striking position with respect to said hammer, electro-magnetic operating means for said hammer and arranged to reciprocally actuate the same, said hammer having an air pocket formed therein with air ducts communicating therewith and arranged to be closed by the movement of the hammer in one direction and creating an air pressure within the pocket whereby to serve as a cushioning means limiting the movement of the hammer in such direction and adapted through the expansion of the air to facilitate the actuation of the hammer.

3. In a device of the class described, a housing, a striking hammer arranged therein, a tool extending through the housing in

striking position with respect to said hammer, electro-magnetic means adapted to reciprocally actuate said hammer, and comprising an armature core connected with the hammer, an armature winding therefor, contact means secured to said core, an armature shaft extending through the sleeves and the core and arranged to slidably carry the latter, field coils disposed within the housing operatively arranged with respect to said armature, an electrical connection for the armature and the field coil, means for reversing the flow of current therethrough, and a cushioning device for the striking hammer comprising an air pocket formed between the hammer and the armature shaft and having air ducts communicating therewith and adapted to be closed by the upward movement of the hammer whereby to cause the formation of an air pressure between the hammer and said shaft.

4. In a device of the class described, a housing, a striking hammer arranged therein, a tool extending through the housing in striking relation with said hammer, electro-magnetic means operatively connected with said hammer and adapted to reciprocally actuate the same and comprising an armature core attached to the hammer, an armature winding therefor, an armature shaft fixedly secured to the housing and arranged to slidably carry said core, electric contact sleeves carried at the upper ends of said core, contact brushes for said sleeve, field coils arranged within the housing and operatively disposed with respect to said armature, an electrical connection for the armature and said field coils, means for reversing the flow of current therethrough whereby to effect a reciprocal movement of the armature core, an air pocket formed between the lower end of the armature shaft and the striking hammer, air ducts extending through the armature core communicating with said pocket and adapted to be closed upon the upward movement of the hammer, such movement of the hammer operating to create an air pressure within the pocket forming a cushioning medium between the shaft and the hammer to prevent striking contact therewith and adapted through the expansion of the air to facilitate the actuation of the hammer in a direction for striking engagement with the tool.

5. An electro-magnetically operated hammer including a series of stationary electro-magnets and a movable armature operatively associated therewith and having a hollow core, a hammer head carried by the armature, said head forming a closure at the lower end of the core, a stationary shaft forming a guide for the core and cooperating with the head to form an air compression chamber within the core, said chamber having air outlets extending through the

wall of the core and controlled in their open and closed positions by the movement of the core upon the shaft.

6. An electro-magnetically operated hammer comprising an electrically actuated movable member, a hammer head carried thereby, said member having a hollow core, a stationary shaft providing a slideable mounting for the core and cooperating with the hammer head and forming a compression chamber in the core, said chamber having

ducts extending through the wall thereof and controlled in their open and closed positions by the movement of said core with respect to the shaft whereby to effect a compression of fluid in the chamber for limiting the approach of the hammer head toward said shaft.

In testimony whereof we affix our signatures.

CLARENCE DONALD BEETH, JR.
